UNITED STATES PATENT OFFICE.

PAUL KIRSCHEN, OF DRESDEN, GERMANY, ASSIGNOR TO LINGNER & KRAFT,
OF SAME PLACE.

MEANS FOR CLOSING BOTTLES OR THE LIKE.

SPECIFICATION forming part of Letters Patent No. 634,622, dated October 10, 1899.

Application filed April 15, 1897. Serial No. 632,206. (No model.)

To all whom it may concern:

Be it known that I, PAUL KIRSCHEN, of Dresden, in the Kingdom of Saxony, German Empire, have invented certain new and useful Improvements in Means for Closing Bottles or the Like, of which the following is a specification, and for which there have been obtained patents in Great Britain, No. 8,051, dated March 29, 1897; in Switzerland, No. 14,237, dated March 8, 1897; in Sweden, No. 9,228, dated March 31, 1897; in the German Empire, No. 99,280, dated February 23, 1897; in Russia, No. 1,545, dated January 16, 1899; in Austria, No. 48/2,085, dated April 12, 1898, and in Hungary, No. 9,981, dated October 29, 1897.

A device for closing bottles, flasks, cans, and the like embodying this invention comprises a cap affixed to or forming a fixed part of the mouth or opening of the bottle or other vessel and having an aperture, a cover fitted to the cap to turn thereon and having an aperture corresponding with the aperture in the cap, and a loose imperforate closing-piece placed between the cap and cover and capable of turning with the latter to a position in which it closes the aperture in the cap or to a position in which it leaves the said aperture open for the purpose of allowing the contents of the bottle or vessel to flow out in a stream or in drops.

The device may be constructed of various forms, as hereinafter described with reference to the accompanying drawings, and it may be employed to tightly close not only bottles, cans, and the like containing liquids, but even those containing gases under pressure.

Figures 1, 2, and 3 show the separate parts of one example of my invention, Fig. 1 representing a plan view of the cap and a section in the line *x* *x*, Fig. 2 a plan view of the cover and a section in the line *y* *y*, and Fig. 3 a side view of the movable closing-piece. Fig. 4 represents a central section of the said parts combined. Figs. 5, 6, 7, 8, and 9 represent central sections of as many examples illustrating modifications of the invention. Fig. 10 represents a plan and a central section of another modification.

Referring first to Figs. 1, 2, 3, and 4, A is

the cap, which is intended to be mounted and fixed with its cylindrical portion directly on the mouth or opening of the bottle or other vessel to be closed. This cap is provided with an eccentric aperture *a*.

B is the cover, provided with the two apertures *b* and *c* and having its edge bent over the flange of the cap in such a manner as to allow of the cover turning on the cap. Before the cover is placed into position there is inserted between it and the cap the loose imperforate closing-piece *d*, which has a flat under surface bearing upon the cap and a convex upper surface projecting into the aperture *b* of the cover.

The loose imperforate closing-piece *d* needs to be only of such size that its under surface is capable of completely covering the aperture *a* in the cap A, while its convex upper surface projects slightly through the aperture *b* of the cover, so that the cover when it is turned will carry the closing-piece with it.

In the position of the parts shown in Fig. 4 the closing-piece *d* closes the aperture *a*. If the cover be turned so as to bring the aperture *c* in the cover over the aperture *a*, the contents of the bottle can then pass out.

From the above it will readily be understood that the lower surface of the closing-piece *d*, which is situated between the cover and the cap and is capable of moving with the cover, constitutes the closing element and will act as such each time when the cover is in a suitable position relatively to the cap, because the smooth under surface of the closing-piece *d* will always follow up any bending of the surface of the cap, it being in this connection immaterial whether the cover B is exactly parallel to that surface of the cap in which the outflow-aperture is provided. The smooth under surface will also always effect a tight closure of the outflow-aperture *a* in the cap A, even when the closing-piece is made of other shapes, of which a few are shown by way of example in Figs. 5 to 10.

In Fig. 5 the upper surface of the piece *d* is shown recessed. Into this recess there extends a stud, projecting from the cover in such a manner that when the cover is turned the closing-piece *d* is moved over the outflow-aperture *a* of the cap in order to close the

bottle or is moved away from said outflow-aperture in order to open the bottle.

In Fig. 6 the closing-piece *d* is shown formed as a plate, which is held against the surface of the cap by means of a coiled spring. In Fig. 7 there is a similar plate *d*, held by means of a leaf-spring. In both cases the plate *d* is moved by turning the cover *B*.

In Fig. 8 the closing-piece *d* is of triangular form in cross-section and enters with its apex or upper edge into a correspondingly-formed recess in the interior of the cover, which moves the closing-piece *d* with it in its rotation.

An elastic material—such as rubber, leather, cork, &c.—may also be inserted between the cover and the plate-shaped closing-piece *d*, as shown in Fig. 9.

If it is desired to have the outflow-aperture in the center of the closing device, this may be done, as shown in Fig. 10, by pivoting the part *B'*, that carries the closing-piece *d* and which may be considered as the equivalent of the cover *B*, eccentrically to the outflow-aperture of the cap.

In all the modifications the smooth flat under surface of the loose imperforate closing-piece *d*, moving with the cover *B* or its equivalent, serves to close the outflow-aperture in the cap.

What I claim as my invention is—
A device for closing a bottle, flask or other vessel, consisting of a cap affixed to the mouth or opening of the vessel and having an aperture, a cover fitted to said cap and having a corresponding aperture, and a loose imperforate closing-piece attached to the cover between it and the cap and capable of turning with the cover to a position in which it closes the aperture in the cap or to a position in which it leaves the said aperture open, substantially as herein described.

In testimony that I claim the foregoing as my invention I have signed my name in presence of two subscribing witnesses.

PAUL KIRSCHEN.
